UNITED STATES PATENT OFFICE.

JEAN-BAPTISTE CAMET, OF BAYONNE, FRANCE.

PROPELLER.

1,201,251.

Specification of Letters Patent. Patented Oct. 17, 1916.

Application filed January 3, 1914. Serial No. 810,113.

To all whom it may concern:

Be it known that I, JEAN-BAPTISTE CAMET, citizen of the French Republic, residing at 3 Rue Pontrique, Bayonne, Basses-5 Pyrénées, France, have invented new and useful Improvements in Propellers, of which the following is a specification.

This invention relates to a propeller which is composed of two separate parts 10 namely: 1,—a semicylindrical case closed on three sides; 2,—a shaft with two or three or four paddles mounted in said case. In order to operate this apparatus must be submerged completely in the liquid or fluid and 15 be mounted at the place where usually the propeller screw is positioned for which this apparatus is substituted. The paddles revolve always in the same direction and strike the fluid after the manner of wings or fins. 20 As soon as the paddles get into the casing, they do not act until they come again out of said casing. Steering is effected by turning the casing which has simply to be turned upside down in order to reverse the direction 25 of movement.

In order to clearly explain the invention several forms of construction are shown in the accompanying drawings, all forms of construction being based upon the principle 30 hereinbefore mentioned and given by way of example only.

In the accompanying drawings:—Figures 1, 2 and 3 are perspective views of a propeller with 2, 3 and 4 paddles respectively. 35 Figs. 4, 5, 6 and 7 are plan views of the propeller Fig. 1 representing the casing in different positions. Fig. 8 is a perspective view of a double propeller. Figs. 9, 10 and 11 are plan views of the double propeller in 40 different positions. Fig. 12 is a perspective view of another form of construction. Figs. 13 and 14 are plan views of the propeller of Fig. 12.

The propellers of Figs. 1, 2 and 3 consist 45 of a semicylindrical casing 1 with end plates 2 in which the bearings 3 for the vertical shaft are arranged. This shaft has, according to the work to be expected from the propeller 2, 3 or 4 blades 4 which always 50 turn in the same direction striking the fluid like the fins of fishes or the wings of birds. Every time a saddle penetrates into the casing 1 its effect is neutralized but it begins to act again as soon as it gets out of the casing. 55 This propeller is submerged completely in the fluid in which it has to work and it is

mounted at the place where the screw-propeller is usually mounted. The casing 1 according to the position which it adopts, produces a forward or backward movement in 60 all the directions of the same plane. If the casing is in the position shown in Fig. 4 the vessel moves in the direction of the arrow A. If the casing 1 is moved in the direction X (Fig. 5) the vessel no longer moves 65 in the direction of the arrow A but in the direction of the arrow B and so on. Fig. 6 shows that the direction in which the vessel moves, that of the arrow C, is opposite to the direction of the arrow A (Fig. 4). If 70 the casing 1 is turned, the engine is not stopped so that the paddles 4 turn always in the same direction. This apparatus therefore permits doing away with the rudder generally used, which can act only through 75 the resistance which it offers and consequently reduces the speed. The propeller axis can be arranged either vertically or horizontally according to its application but if it has to work in the water it is preferably 80 arranged vertically in order to permit the steering in any direction.

Fig. 8 shows a double propeller and the positions of the casings 1 with regard to one another if the vessel has to move in the direction of the arrow D, Figs. 9, 10 and 11 showing the positions of the casings if the vessel has to move in other directions.

Fig. 12 shows a double superposed propeller and Figs. 13 and 14 illustrate the positions which the casings 1 must adopt for the different directions.

The shafts 3 turn in opposite directions in order to obtain a regular forward movement.

If the propeller has to work in the air its axis is preferably mounted horizontally in order to produce the ascension. If the propeller is double, motion similar to the flapping of wings is obtained. By turning the 100 two casings in the same directions an oblique ascension is obtained and by turning the same farther, the movement in horizontal direction is insured. By turning the same upside down the horizontal movement in 105 reverse direction is obtained.

It has to be understood that the invention is not strictly limited to the examples described but that it can be applied for any kind of shipping and that its application to 110 dirigible balloons will permit them to immediately reascend, if for example the landing

could not be properly effected, and that the shapes, dimensions, arrangements and materials can vary according to the applications of the invention.

5 I claim—

A propeller comprising a pair of semi-cylindrical casings having end plates provided with projecting bearings intermediate thereof, shafts journaled in said bearings and disposed in parallel relation and 10 paddles fixed to the shafts for rotation therewith, said paddles being operative ex-

teriorly of the casing and inoperative interiorly of the casing, said casings being supported in superposed relation and said casings being turnable on said shafts. 15

In testimony whereof I have signed my name to this specification in the presence of two subscribing witnesses.

JEAN-BAPTISTE CAMET.
